UNITED STATES PATENT OFFICE.

HALFDAN A. STEEN, OF MILWAUKEE, WISCONSIN, ASSIGNEE TO ALLIS-CHALMERS COMPANY, A CORPORATION OF NEW JERSEY.

RHEOSTAT.

1,016,793.

Specification of Letters Patent.

Patented Feb. 6, 1912.

Application filed August 1, 1910. Serial No. 575,023.

To all whom it may concern:

Be it known that I, HALFDAN A. STEEN, a subject of King of Norway, residing at Milwaukee, in the county of Milwaukee and 5 State of Wisconsin, have invented certain new and useful Improvements in Rheostats, of which the following is a full, clear, and exact specification.

My invention relates to means for regulating and controlling electric circuits, and more particularly to rheostats.

In the operation of electric translating devices of various sorts, a very close regulation of current is often required, and in 15 some cases it is necessary that the increase or decrease of current be continuous, that is, unspasmodic. With the ordinary rheostat a fairly close regulation of current may be obtained by dividing the resistance into a 20 great number of steps, but this construction is expensive and there is a marked increase or decrease of current at each step.

The object of my invention is to provide an ordinary rheostat having a resistance divided into a small number of steps with an arrangement which will make possible a close and continuous adjustment of the resistance.

With this object in view I provide a main 30 variable resistance and an auxiliary resistance, and means for interconnecting and varying said resistances in such a way that the adjustment is continuous. The auxiliary resistance is preferably a compressible 35 resistance, although for some features of my invention this is not essential.

The various novel features of my invention will appear from the description and drawings, and will be particularly pointed 40 out in the claims.

Figure 1 is an elevation of a rheostat embodying my invention, parts being shown in section for the sake of clearness; and Figs. 2, 3, 4, and 5 are diagrammatic views 45 of my rheostat showing connections in different positions.

A main resistance 10, a compressible resistance, such as a carbon pile 11, and the parts coöperating with said resistances are 50 mounted upon an insulating base 14. The main resistance 10 is divided into a number of sections by contacts 12^a, 12^b, 12^c, and 12^d arranged in a circular row, and these sections may be cut into or out of circuit by the 55 movement of an arm 13 carrying a brush 13^a.

The carbon pile 11 consists of a number of carbon disks 15, which are preferably inclosed in, but insulated by insulation 15^a from a metal tube 16 having a number of circular cooling flanges 17. The ends of 60 this tube 16 are closed and supported by caps 18 and 20, secured to the base 14. An adjusting screw 19 passes through the cap 18 and varies the position of the upper end of the pile 11, while a plunger 21 passes 65 through the cap 20 and bears against the lower end disk of such pile. One end of the plunger 21 is connected to a toggle 22, at the knee of which is a roller 22^a which rides on the periphery of a cam 23. The cam 23 70 is secured to a shaft 24 and is rotated by any suitable means, such as an operating handle 25.

Secured to the movable arm 13 and insulated therefrom by insulation 13^b is a 75 bridging member 26, having one brush 26^a which engages the contacts 12 and another brush 26^b which engages a curved bar 27. One end of the carbon pile 11 is electrically connected to the bar 27, and the other end 80 to the arm 13. The space between successive contacts 12 is greater than the width of either brush 13^a or 26^a, so that neither of said brushes will ever bridge two of the contacts.

The arm 13 is moved intermittently by any suitable device, such as a Geneva gear, which consists of a driving portion mounted upon the shaft 24 and a driven portion secured to the arm 13. The driving portion 90 comprises a pin or tooth 28 and circular segment 29, and the driven portion a circular segment 30 having a number of notches 31 and concave portions 32. When the shaft 24 is rotated, the pin 28 at each 95 rotation engages one of the notches 31 and moves the arm 13 one step forward or back. When the pin 28 is out of engagement with the notches 31 the circular segment 29 engages one of the concave portions 32 and 100 locks the arm 13.

In Fig. 1, the rheostat is shown in its off position. In this position the carbon pile 11 is released and the brushes 13^a and 26^a are 105 out of engagement with the resistance contacts. If the operating handle 25 is rotated in a counter-clockwise direction, the pin 28, which is in engagement with one of the notches 31 of the member 30 moves the arm 13 in a clockwise direction until it assumes 110

the position shown in Fig. 2. This puts the carbon pile 11, which has not yet been compressed, in series with the main resistance 10, and the total resistance of the rheostat is 5 at its maximum. After the arm 13 has been moved to the position shown in Fig. 2, further counter-clockwise movement of the handle 25 disengages the pin 28 from the notch 31, and brings the circular segment 29 into 10 engagement with the concave portion 32 to lock the arm 13 for the time being against further rotary movement. Also, acting through the cam 23 and the toggle 22 the continued movement of the handle 25 gradually 15 compresses the carbon pile 11 to decrease its resistance, until when the maximum pressure on the carbon pile is applied, the pin 28 has engaged the next notch in the member 30 and has thereby moved the arm 20 13 to the position shown in Fig. 3. When the arm 13 assumes the position shown in Fig. 3, the brushes 13^a and 26^a both engage the contact 12^a, short-circuiting the carbon pile and allowing the current to pass along 25 the arm 13 and through the whole of the resistance 10. The pin 28 being still in engagement with the member 30, a continuation of the movement of the operating handle in a counter-clockwise direction brings 30 the arm 13 into the position shown in Fig. 4, whereupon the pin leaves the notch in the member 30 and the segment 29 locks the arm for an interval against further movement. During the early part of this last movement, 35 and before the brush 26^a engages the contact 12^b the carbon pile is released, due to roller 22^a engaging the hollow part of the cam to bring it to its maximum resistance value. In the position shown in Fig. 4 the brush 26^a 40 is engaging contact 12^b, and brush 13^a is engaging contact 12^a, the carbon pile 11 thereby being connected in parallel with the first section of the resistance 10, causing the total effective resistance of the rheostat to be 45 gradually and unspasmodically decreased. If a cycle the same as that used in passing between the positions shown in Figs. 2 and 4 is now repeated, the first section of the resistance 10 will be cut out of circuit, causing 50 another gradual decrease in the effective rheostat resistance. The carbon pile 11 will first be gradually compressed, thus reducing its resistance and shunting more and more current around the first section of the resistance 55 10 until, when the pile has been compressed to its maximum, such section is practically short-circuited. The arm 13 is moved to the position shown in Fig. 5, in which position the brushes 13^a and 26^a both engage the contact 12^b to short-circuit the carbon pile. The 60 first section of the resistance 10 is now cut out of circuit. By continuing the movement of the operating handle in a counter-clockwise direction, the carbon pile will be first released, and then connected in parallel with

the next section of resistance, then compressed to shunt current away from such section, and then short-circuited. This may be repeated for each section of the resistance. The operating handle may be stopped at any 70 desired point leaving any desired amount of resistance in the circuit. The variation in the resistance is extremely gradual, there being at no time a decided change in the value of effective resistance. The resistance in circuit is thereby continuously or unspasmodically varied. For cutting resistance into circuit, the operating handle is rotated in the clockwise direction, producing results just the reverse of those described above. 75

I have described my invention in what I now consider to be the preferred form, but many modifications may be made in the precise arrangement shown and described and all such which do not involve a departure 80 from the spirit and scope of my invention I aim to cover in the following claims.

What I claim as new is:

1. In a circuit-controlling device, the combination of a main resistance, a compressible auxiliary resistance, means for connecting said compressible resistance in parallel with portions of said main resistance, and means for compressing said compressible resistance. 90

2. In a circuit-controlling device, the combination of a main resistance, means for cutting into or out of circuit portions of said main resistance, a compressible auxiliary resistance, means for connecting said compressible resistance in parallel with portions of 95 said main resistance, and means for compressing said compressible resistance. 100

3. In a circuit-controlling device, the combination of a main resistance, an auxiliary resistance capable of being continuously adjusted, means for adjusting said auxiliary resistance, and means operated by said adjusting means for cutting into or out of circuit portions of said main resistance. 105

4. In a circuit-controlling device, the combination of a circular row of contacts, resistance sections connected between successive pairs of said contacts, two brushes for successively engaging said contacts, said brushes being insulated from each other, a compressible resistance connected between 115 said brushes, a device for compressing said resistance, and means actuated by said device for operating said brushes. 110

5. In a circuit-controlling device, the combination of a main resistance, an auxiliary compressible resistance, means for intermittently connecting portions of said main resistance in parallel with said compressible resistance and for varying said main resistance, and means for intermittently compressing said compressible resistance and operating the aforesaid means. 120

6. In a circuit-controlling device, the combination of a main resistance, a continuously 125

variable auxiliary resistance, and means associated with said main resistance for connecting said auxiliary resistance in parallel with a section of said main resistance and for varying said auxiliary resistance.

5 7. In a circuit-controlling device, the combination of a main resistance, a continuously variable auxiliary resistance, a movable member for varying said main resistance and for connecting portions of said main resistance in parallel with said auxiliary resistance, a device for varying said auxiliary resistance, and means interlocking with said device for operating said movable member.

10 8. In a circuit-controlling device, the combination of a main resistance, and means including a pressure varying member for establishing a shunt circuit around a portion of said resistance and continuously varying 20 the resistance of said shunt-circuit.

15 9. In a circuit-controlling device, the combination of a main sectional resistance, an auxiliary compressible resistance, means for connecting said auxiliary compressible resistance in series with a variable amount of 25 said main resistance, and means for varying the compression of said compressible resistance.

20 10. In a circuit-controlling device, the combination of a main resistance, a variable auxiliary resistance, means for cutting into or out of circuit portions of said main resistance and for connecting said auxiliary

resistance in parallel with portions of said main resistance, and means for regularly and 35 intermittently operating said first mentioned means.

11. In a circuit-controlling device, the combination of a main resistance, a variable auxiliary resistance, means for cutting into 40 or out of circuit portions of said main resistance, and for connecting said auxiliary resistance in parallel with portions of said main resistance, and also for intermittently short circuiting said auxiliary resistance. 45

12. In combination, a main sectional resistance, and means including a cam operated member for establishing a single-path shunt circuit around a portion of such resistance and for varying the resistance of 50 such shunt circuit.

13. In combination, a main resistance, an auxiliary resistance, and means during a single operation thereof for rendering in order said auxiliary resistance its maximum 55 effective value, connecting it in parallel with the main resistance, and reducing said auxiliary resistance to its minimum effective value, and then short-circuiting said auxiliary resistance. 60

In testimony whereof I affix my signature, in the presence of two witnesses.
